UNITED STATES PATENT OFFICE.

JAMES HENRY KANE, OF JERSEY CITY, NEW JERSEY.

COMBINATION PAPER-HANGING TOOL.

1,156,783.

Specification of Letters Patent.

Patented Oct. 12, 1915.

Application filed October 21, 1914. Serial No. 867,738.

To all whom it may concern:

Be it known that I, JAMES H. KANE, a citizen of the United States, and a resident of Jersey City, in the county of Hudson and State of New Jersey, have invented a new and Improved Combination Paper-Hanging Tool, of which the following is a full, clear, and exact description.

This invention relates to improvements in paper tools, and particularly to a paper hanger's tool, and has for an object to provide an improved construction which may be used to accomplish a plurality of results upon the operation of a single handle.

Another object in view is to provide a paper hanger's tool with trimming, cutting and rolling devices which may be operated from a single gripping member.

In the accompanying drawings—Figure 1 is a side view of a tool embodying the invention; Fig. 2 is a top plan view of the structure shown in Fig. 1; Fig. 3 is a section through Fig. 1 on line 3—3; Fig. 4 is a section through Fig. 1 on line 4—4.

Referring to the accompanying drawings by numerals, 1 indicates a handle or gripping member of any desired material which has the end 2 of a knife or cutting member 3 projecting therein. Suitable fastening means, as for instance rivets 4 are provided for clamping the projection or extension 2 to the handle. The knife or cutting member 3 is provided with an edge 5 which is preferably rounded as shown in Fig. 1 so as to easily cut or trim paper along a straight edge. The rounded surface is desirable in that the knife may be rocked for cutting any unevenness or slight puckering of the paper during the cutting operation. Arranged at

the outer end of knife 3 and as far from the edge 5 as possible is a disk 6 provided with an edge 7. Disk 6 is pivotally mounted upon a suitable journal member 8 which is designed to trim or cut the paper along the ceiling, molding or other suitable stop or obstacle. In placing paper upon the wall a paper hanger usually allows a slight overlap

at each end which must be removed by some means, and applicant has in the present construction provided the disk 6 for removing this surplus paper so that the paper remaining on the wall will fit exactly the space desired. In order to cause the edges of the paper to properly adhere to the wall, roller 9 is provided formed with a suitable covering of any material, as for instance rubber. A pivotal member 10 extends through roller 9 and fits in the brackets 11 and 12 which have extensions 13 and 14 secured to the extension or projection 2 by suitable rivets 15. It will be noted that the various devices necessary to properly prepare a strip of paper and apply the same are connected with a single member, namely, knife 3 or the extension thereof so that a single handle 1 may operate any and all of the devices in the desired sequence, namely, the edge 5, then the edge 7 of disk 6 and finally the roller 9.

What I claim is—

1. In a paper hanger's tool, a flat blade for trimming the edge of a strip of paper, a wheel journaled on said blade formed with a cutting edge for trimming the ends of said strip of paper, a roller connected with one end of said knife and a single handle for operating all of said devices.

2. In a device of the character described, a flat knife formed with a rounded cutting edge, a disk formed with an edge at its periphery, means for pivotally mounting said disk at one end of said knife, a pair of brackets rigidly secured to said knife near the shank, a roller journaled in said brackets, and a handle rigidly secured to the shank of said knife so as to operate said knife, said roller and said disk.

In testimony whereof I have signed my name to this specification in the presence of two subscribing witnesses.

JAMES HENRY KANE.
